UNITED STATES PATENT OFFICE.

BOY CONNELL, OF BUFFALO, NEW YORK.

COMBINATION TERMINAL BLOCK AND LIGHTNING-ARRESTER.

1,328,720.

Specification of Letters Patent. Patented Jan. 26, 1920.

Application filed June 20, 1919. Serial No. 305,604.

To all whom it may concern:

Be it known that I, ROY CONNELL, a citizen of the United States, and resident of Buffalo, in the county of Erie and State of New York, have invented a certain new and useful Combination Terminal Block and Lightning-Arrester of which the following is a specification.

This invention relates to a combination terminal block and lightning arrester.

The object of the invention resides in so constructing the device that it will operate as an ordinary terminal block, normally, but will permit the grounding of high potential discharges to protect the circuit in which it is interpolated.

I accomplish this object broadly by interposing a resistance element of carborundum or the like between the two binding posts of the terminal block, using one of the binding posts for the connection to the line and to the relay and grounding the other binding post.

Furthermore, the carborundum resistance element is interposed between the binding posts in such manner that it may be readily applied and so that it will not interfere with the normal function of the binding posts.

30 In the drawing:

Figure 1 is a side elevation of a device constructed in accordance with my invention;

Fig. 2 is a top plan view of the same;

35 and

Fig. 3 is a fragmental detail. The form of the invention illustrated in the drawing includes a base 1 of suitable insulating material, such as porcelain or the like, on which are mounted two binding posts 2 and 3, which are arranged in spaced relation to each other and extend above the upper face of the base. A pair of collars 4 encircle the binding posts 2 and 3 and rest upon the bosses 5 of the base. Between these collars is interposed the resistance element 6 which is made, preferably, of carborundum. The ends of this resistance element are provided with seats 7 to closely fit against the outer faces of the collars. Lock nuts 8 are mounted on the binding posts above the collars 4. Between the upper edges of the collars and the lock nuts 8

brass washers 9 are interposed, and these washers are of greater diameter than the 55 collars. Thus, when the nuts 8 are in their locking positions and the carborundum block or resistance element is in place, the displacement of the element will be prevented. Binding nuts 10 are also mounted 60 on the binding posts 2 and 3 and interposed between the lower ends of these nuts and the upper faces of the nuts 8, are additional brass washers 11, between which the wires from the line, to the relay and to the 65 ground are engaged and securely clamped in the usual manner.

In Fig. 2 of the drawing I have shown three of the devices which are arranged in parallel, the grounded terminals 2 being connected together by a conductor 12. It will be readily realized that the device may be used singly or may be connected to other similar devices if desired. 70

similar devices if desired. When a normal voltage is used the current will flow through the line and relay wires and through the binding post to which they are attached, but the circuit will not be grounded because of the high resistance of the carborundum element 6. However, when the voltage is increased to an abnormal extent, the current will flow through the carborundum resistance element and will be grounded through the binding post 2 and the ground wire connected thereto, so that the circuit from the line to the relay will be protected. Thus it will be seen that I have constructed a combination terminal block and lightning arrester in which the resistance element, which permits the high potential discharges alone, is interposed between the binding posts of the block in a novel and simple manner.

What I claim is:—

What I claim is:—

1. A combination terminal and lightning 95
arrester, comprising an insulating base, a
pair of binding posts mounted thereon, col-
lars surrounding said binding posts and lock
nuts for clamping the collars in position,
binding nuts on the posts, and a resistance 100
block extending between and having its
ends embracing the collars.

ends embracing the collars.

2. A combination terminal and lightning arrester, comprising an insulating base, a pair of binding posts mounted thereon, 105 collars surrounding said binding posts, a

resistance element extending between and having its ends embracing the collars, and lock nuts on the binding posts arranged to clamp the collars in place and to prevent movement of the resistance element longitudinally of the binding posts.

Signed at Buffalo, in the county of Erie

and State of New York, this 22nd day of May, A. D. 1919.

ROY CONNELL.

Witnesses:

RUTH SMITH,
Geo. R. Rix.
